UNITED STATES PATENT OFFICE.

FERDINAND MORA CANDA, OF NEW YORK, N. Y.

BALL-ROLLING APPARATUS.

Application filed October 21, 1919. Serial No. 332,264.

To all whom it may concern:

Be it known that I, FERDINAND MORA CANDA, a citizen of the United States of America, and a resident of New York, in the county of New York and State of New York, have invented certain new and useful Improvements in Ball-Rolling Apparatus, of which the following is a specification.

My invention relates to apparatus for forming balls, and is particularly intended for forming, from wrought iron or steel, balls adapted to be used in crusher mills and the like, but is also adapted and intended for forming balls of other materials and for other uses,—for example, lead shrapnel bullets, lead shot, glass balls of various types and uses, etc. My invention comprises coacting grooved ball-forming rolls, together with means for moving one of said rolls toward and from the other, and means for holding in place between said rolls the rod or the like from which the balls are being formed. Other features of my invention will be pointed out hereinafter.

The object of my invention is to form balls, particularly of iron or steel, relatively inexpensively, rapidly, and by simple apparatus.

I will now proceed to describe my invention with reference to the accompanying drawings, and will then point out the novel features in claims. In said drawings:

Figure 1 shows a side elevation and partial transverse section of my improved ball rolling apparatus; Figure 2 shows a top view of said apparatus, the upper "locator" being partly broken away, and the means for raising and lowering said locator being omitted but indicated in dotted lines. Figure 3 shows a detail fragmentary transverse section through the rolls and locators, indicating an alternative form of locator, the section being taken on the line 3—3 of Figure 4; and Figure 4 shows a fragmentary transverse section on the line 4—4 of Figure 3.

In the drawings, 1 designates a suitable frame for the machine, and 2 and 3 indicate grooved coacting ball-forming rolls, mounted in suitable bearings 4 and 5, bearings 5 being mounted to slide in ways in frame 1, and suitable means, as for example, ram devices 6 controlled by a valve 7, being provided for so sliding said bearings 5 and the roll 3. These ram devices 6 may be considered diagrammatic illustrations of any

suitable means for moving the roll 3 toward and from the roll 2, and I do not limit myself to any particular means for the purpose.

8 and 9 designate what I term "locators" for determining the position between rolls 2 and 3 of the material to be rolled into balls, and for preventing the escape of the balls until such escape is desired. In the arrangement shown in Figures 1 and 2, these locators may be transverse frames carrying idler rollers 10; or, as indicated in Figures 3 and 4, these locators, there designated as 8^a and 9^a, may have comb-teeth 10^a in lieu of rollers 10. For adjustment, ram-devices 11 and 12 may be provided for these locators controlled by a valve in the manner previously described in regard to the ram devices 6; also, the ram devices 11 and 12 may be considered as diagrammatic representations of any suitable means for moving the locators in and out, and I do not limit myself to any particular means for the purpose.

I have not indicated any particular means for rotating rolls 2 and 3, but may employ for the purpose the means commonly employed for rotating the rolls of ordinary rolling mills; except that rolls 2 and 3 should be rotated in the same direction, as indicated by arrows in Figure 1. At the sides of roll 3 are hook-shaped members 13 which serve as primary supports and locators for the bars from which the balls are to be formed.

The operation of my improved ball-rolling machine is as follows: Roll 3 having been retracted, a bar of material to be rolled into balls is introduced between rolls 2 and 3, such bar resting on the members 13, and roll 3 is then advanced to press said bar against roll 2. Rolls 2 and 3 being in rotation, the said bar is rotated between rolls 2 and 3, and by the pressure exerted by said rolls, and the grooving action of the ribs 10^a of said rolls, the material of said bar is forced into the grooves of said rolls during its rotation, being caused to take a form corresponding to that of the grooves of said rolls, and so becoming a series of ball-like objects connected by narrow necks; which necks are finally severed or broken as the rolling of the balls proceeds, after which the separated balls usually turn to new axes of rotation, so that the tests (the remnants of the said necks) at the former axis of rotation of each ball are rolled into the body

of the ball, and the metal of the balls is condensed and rendered solid throughout. Of course, in the case of iron or steel, glass, or similar materials, the bar is, at the time of introduction, in a heated condition suitable for rolling. Commonly, in the case of iron or steel, and similar materials, the initial diameter of the bar is somewhat less than the diameter of the finished balls, the metal being pressed toward the equatorial portions of the balls from the sides thereof during the rolling operation, so that the ball-sections increase somewhat in diameter as the metal enters deeply into the grooves of rolls 2 and 3 and attain ball-form; though if the material treated be of somewhat spongy nature, so as to be capable of a considerable degree of compression and condensation, it is possible that the initial diameter of the bar may be the same as, or even greater than, that of the finished ball.

During the rolling operation, the locators, 8 or 9, or 8^a and 9^a, in connection with the side locators 13, keep the material being acted upon in proper position between rolls 2 and 3, preventing that material from passing down from between said rolls, or from being squeezed up from between said rolls; and if necessary or desirable, the positions of said locators 8 and 9 may be adjusted during the rolling operation; for example, as the diameters of the balls increase it may be desirable to slightly retract the said locators in approximate accordance with such increase in diameter. When the balls are completed, roll 3 is retracted and the balls drop out from between rolls 2 and 3, while the "crop ends" of the bar, resting on members 13, drop off from said members, or are knocked off therefrom, and a new bar is introduced and the operation repeated.

The machine above described is one in which the operation of rolling the balls is very completely under the control of the operator, who may advance or retract roll 3, and locators 8 and 9, or 8^a and 9^a, as required to regulate properly the pressure exerted on the material being treated, or the time of treatment. He can regulate the time during which the material is being rolled between the rolls in accordance with the degree of hardness of the material as determined either by its nature or its temperature; in a word, the machine is a true machine tool, as distinguished from a mere automatic machine. In a companion case patented February 1, 1921, No. 1,367,299, I have illustrated and described a ball rolling machine comprising coacting grooved ball-forming rolls, in connection with an adjustable presser adapted to press the material acted upon against said rolls. In that machine, the pressure required to be exerted on the material acted on is exerted in the main by the said presser, without any intended

movement of one of said rolls toward or from the other except such as may occur, as in ordinary rolling-mill practice, due to presence of springs or the like in the bearing-structure of the mill. In the ball-rolling machine of the present application, however, the action of the machine is regulated and determined by advance and retraction of roll 3, the locators 8 and 9, or 8^a and 9^a, being employed mainly to keep the material acted on in proper place between rolls 2 and 3, and being adjusted in position, if at all, during the rolling operation, merely to regulate the position of the material being acted on, or to prevent such undue pressure on the material, during the increase of diameter thereof, as might prevent proper formation of the balls.

What I claim is:—

1. In a ball rolling apparatus, the combination of coacting grooved ball-forming rolls, manually controlled means for separating the same and bringing them together, and adjustably controlled locating means for determining the position between said rolls of material to be acted upon. 85

2. In a ball rolling apparatus, the combination of coacting grooved ball-forming rolls, one of which is mounted to be moved toward and from the other, manually controlled means for so moving such roll, and adjustably controlled locating means for determining the position between said rolls of material to be acted upon. 95

3. In a ball rolling apparatus, the combination of coacting grooved ball-forming rolls, manually controlled means for separating the same and bringing them together, and an adjustably controlled locator on one side of said rolls for determining the position between said rolls of material to be acted upon. 100

4. In a ball rolling apparatus, the combination of coacting grooved ball-forming rolls, manually controlled means for separating the same and bringing them together, and adjustably controlled locators on opposite sides of said rolls for determining the position between said rolls of material to be acted upon. 110

5. In a ball rolling apparatus, the combination of coacting grooved ball-forming rolls, manually controlled means for separating the same and bringing them together, and an adjustably controlled locator on one side of said rolls for determining the position between said rolls of material to be acted upon, said locator comprising a rotary roller adapted to bear on the said material. 120

6. In a ball rolling apparatus, the combination of coacting grooved ball-forming rolls, manually controlled means for separating the same and bringing them together, and adjustably controlled locators on oppo- 130

site sides of said rolls for determining the position between said rolls of material to be acted upon, said locators each comprising a rotary roller adapted to bear on the said material.

- 5 7. In a ball rolling apparatus, the combination of coacting grooved ball-forming rolls, manually controlled means for separating the same and bringing them together, an 10 adjustably controlled locator on one side of said rolls for determining the position between said rolls of material to be acted upon, and manually controlled means for moving said locator in and out.

- 15 8. In a ball rolling apparatus, the combination of coacting grooved ball-forming rolls, and locating means at the sides of said rolls adapted to receive and support the ends of a bar which may be introduced between said rolls.

- 20 9. In a ball rolling apparatus, the combination of coacting grooved ball-forming rolls, a frame having bearings for one of said rolls and having ways in which may

slide bearings for the other of said rolls, 25 slideable roll bearings in said ways, manually controlled means for moving said bearings back and forth, and adjustably controlled locating means for material between said rolls.

10. In a ball rolling apparatus, the combination of coacting grooved ball-forming rolls, a frame having bearings for one of said rolls and having ways in which may slide bearings for the other of said rolls, 25 slideable roll bearings in said ways, manually controlled means for moving said bearings back and forth, adjustably controlled locating means for material between said rolls, and manually controlled means for moving 20 said locating means in and out.

In testimony whereof I have signed this specification in the presence of two subscribing witnesses.

FERDINAND MORA CANDA.
